UNITED STATES PATENT OFFICE.

FRANK J. MURPHY, OF SOUTH BOSTON, MASSACHUSETTS.

GOLF PRACTICE APPARATUS.

Application filed March 5, 1928. Serial No. 259,366.

This invention relates to golf instruction apparatus and with regard to certain more specific features thereof to a device for training a golf player to hold his head steady 5 while making a swing of the golf club.

Apparatus has been devised heretofore, intended to train golfers in the respect above mentioned, but in every prior instance a means has been provided for definitely restricting the head movement, which defeats the desired end, or the devices have been so arranged that movement of the head disturbs the relation of the ball, so that the shot cannot be perfected.

15 The present apparatus is designed to give the player substantially a free movement of the head, but to signal to the player in advance of the shot should he wrongfully avail himself of this opportunity. It is believed that this method is the only correct way of 20 training a player for future play when the opportunity to use the apparatus is not present.

The present invention has therefore for 25 one of its objects to provide an extremely simple device with a connector to the head or head-gear of the player and a signal which may be audible or visible and which is arranged to notify the player should there 30 be any substantial head movement as the club is approaching and contacting with the ball. It is a further object of the invention to provide such signalling and connecting means as will allow the operator to move 35 his head and body freely as the shot is completed so as to simulate the natural playing conditions.

Other objects will be apparent from the following description.

40 In the accompanying drawing wherein is represented one of various possible embodiments of the invention;

Figure 1 is a view in vertical section of the improved golf instruction apparatus.

45 Figures 2, 3 and 4 are detailed views and part sectional views of the plug or core arranged in the signalling and connecting mechanism.

Figure 5 is a view illustrating the use of 50 the device shown in Figure 1.

Referring now more particularly to the drawings, there is indicated at 10 a hollow base which may be of wood, metal or other suitable material and which has connected therewith a tube 11 with a restricted or detachable top portion or cap 12 having a

small aperture 13 through which a cord 14 is arranged. One end of the cord 14 is connected to a core or plug 15 as at 16, inside the tube 11, and the other end of the cord 14 is connected as at 17 with a spring clip 18.

The plug 15 has an easy sliding fit inside the tube 11 and is frusto-conical at its lower portion as indicated at 20, this being for the purpose of fitting into a similarly shaped 65 aperture 21 in the upper portion of the hollow base 10. The plug 15 has fixed therein a permanent horse-shoe magnet 22 and it is provided with apertures 23 through the conical lower portion and apertures 24 through 70 a top circular portion 25. These apertures permit the escape of air as the plug is lowered into the tube 11. The poles 30 of the magnet are extended slightly below the plug 15 and are adapted to contact magnetically 75 with an armature 31 fixed on a gong striker 32, which latter is pivoted at 33 on an adjustable arm 34. The arm 34 is screwed to a plate 35 which, in turn, is fixed to the inside of the hollow base member 10. This 80 plate 35 carries a gong 36 and a projecting pin 37 which is adapted to intercept the striker 32 as the plug 15, magnetically contacted with the armature 31, lifts the striker. Continued lifting of the plug 15 will strip 85 it from the armature by reason of the contact of the striker with the pin 37. This causes the striker to drop around the pivot 33 and sound the gong 36, there being a spring characteristic to the striker which allows for this contact when it is dropped from its stripping position against the fulcrum point 40 which is provided by slotting one end of the arm 34. Normally, this point 40 will hold the striker slightly out of contact with the gong. These distances can be varied by moving the arm 34 as provided by the screw and slot connections shown in Figure 1.

The apparatus is operated as follows. A 100 golf student takes his stand a suitable distance away from the signalling device according to the position shown in the dotted lines in Figure 5. He then adjusts the spring clip 18 to the visor of his cap or if desired the end of the cord 14 may be provided with a suitable gear for arrangement directly on the student's head. This action involves lifting the plug or core 15 some distance up in the tube 11. The student then addresses 105 the ball which involves leaning forwardly and raising the club to a position beyond the 110

shoulder. He gauges these two positions so that the plug will be dropped in the tube to its seated position in the base 10 and he will be informed of this condition by the magnetic click of the armature 31 against the magnet 22. This position of address is indicated in Figure 5 of the drawings by the full lines. The student then makes a swing undertaking to maintain the head position which he has assumed until after the position of contact of the face of the club with the ball. If there is any inadvertent movement of the head backward or to one side or the other, the cord 14 is pulled lifting the armature 31 until the striker 32 is stripped by the pin 37 and drops back against the gong 36. The test therefore is that the student shall make a swing beyond contacting position without receiving a signal from the device that his head has moved. It will be obvious, however, that after the contacting position has been reached, the student is free to move his head or body to observe the effect of the shot. This involves the lifting of the magnet and the sounding of the gong, but at a time when this signal is immaterial. There are, of course, various mechanical devices which might be employed in place of the magnetic connecting device shown in the drawing as illustrating a preferred embodiment of the invention. Such devices would by the sense of touch or sound indicate to the student the instant that the alarm had been set for operation as in the present form it is indicated by the click of the armature against the magnet and would also pick up the striker by suitable releasing means so that it might be stripped by a pin or other device and the striker dropped by gravity against the gong. It is pointed out, therefore, that while in the preferred form shown and described herein the signalling device is in the nature of an electromagnetically operated audible signal, it is contemplated and is well within the scope of the invention in its broadest aspect that other instrumentalities or devices might be used and the invention would include signalling devices in their nature either audible, visible or informative to the sense of feeling. The characteristic principle of the invention lies more particularly in connecting a signalling apparatus to the student's head in such a way that the head is not confined, but, if inadvertently moved, the signal will be transmitted immediately.

The apparatus is relatively inexpensive to manufacture, simple in its adjustments and adaptability and effective to a high degree.

Having described the invention what I claim is:—

1. In a golf practice apparatus, in combination, signalling means having a movable element, means for connecting said movable element with the head of a person and a de-

vice in said signalling means for informing the person of head movement at any time after the signalling means has been set for operation.

2. In a golf practice apparatus, a signalling device, having a movable element movable toward and from signal setting position, a cord adapted to connect said movable element to the head of the operator, so that by moving the head, the said movable element may bind a position in the signalling mechanism that will cause it to be set for operation and a member thereafter movable under the influence of the first said movable member to operate the signal. 70 75 80

3. In a golf practice apparatus, a stand, comprising a base and a vertical tube, an element arranged in said tube for movement up and down therein and a cord connecting said element with the operator's head, a signalling device which is set in operation by the movement of the element in said tube to its lowermost position and which is operated to give an informative signal as the element in said tube is moved upwardly 90 95 100 therein.

4. In a golf practice apparatus, in combination, a stand comprising a hollow base and an upwardly extending hollow tube, a core member arranged for movement axially in said tube, an audible signalling device arranged in the base of said stand and adapted to be set in operation by the downward movement of said core member in said tube and means for operating said signal as said core member is moved upwardly in said tube. 105 110 100

5. In a golf practice apparatus, a signal stand, comprising in combination a base and a slideway, a signalling mechanism in said base and a member arranged in said slideway for setting and operating said signal and a cord for connecting the setting and operating member with the head or head-gear of a person. 110 105

6. In a golf practice apparatus, a signalling device, comprising a stand having a base and a slideway, a gong arranged on said stand, a signal setting and operating member arranged in said slideway, magnetic means for connecting said signal setting and operating member with the direct signalling element, a cord connecting said signal setting and operating member with a person's head and means to break the magnetic connection as the operator's head is moved. 115 120 125

7. In a golf practice apparatus, a signalling mechanism, a movable element therein adapted upon movement in one direction to set the signalling mechanism in condition for operation and upon movement in the other direction to operate the signal in combination with flexible connecting means between said member and the head of a person. 125 130

8. In a golf practice apparatus, in combination, a base, a tube extending upwardly therefrom, a gong arranged on said base, an adjustable striker arranged adjacent said gong, a plug arranged for movement up and down in said tube and having a magnet in the lower end thereof, an armature on said striker, means for breaking said contact as the plug is moved in one direction in the tube.

9. In a golf practice apparatus, a flexible cord having one end provided with means

for attachment to the head of a person and the other end provided with a movable element, guiding means for said movable element, a signalling device, and means whereby movement of the person's head allows movement of the movable element in said guideways to set the signalling means for operation, and whereby movement of the person's head thereafter, in another direction, actuates said movable element to cause operation of said signalling means. ¹⁵ ²⁰
